UNITED STATES PATENT OFFICE.

BELLE HURT, OF INDIAN, VIRGINIA.

TOWEL-RACK.

1,118,553.

Specification of Letters Patent.

Patented Nov. 24, 1914.

Application filed March 21, 1914. Serial No. 826,280.

To all whom it may concern:

Be it known that I, BELLE HURT, a citizen of the United States, residing at Indian, in the county of Tazewell and State of Virginia, have invented certain new and useful Improvements in Towel-Racks, of which the following is a specification, reference being had to the accompanying drawings.

This invention relates to towel racks.

10 The object of the invention is to provide a simple and readily constructed form of towel rack, adapted for the two-fold purpose of hanging towels to be subjected to the action of the atmosphere for the purpose 15 of drying, and also for maintaining them in folded position and in such manner as to shield them from dirt or dust.

With the above and other objects in view, as will appear as the nature of the invention 20 is better understood, the same consists, generally stated, in a towel rack or container comprising, essentially, a plurality of sections composed of pairs of flat members of greater length than an ordinary towel, each 25 pair being hinged together independently, and the whole series being connected in such manner as to permit ready access to any one container when it is desired either to position or remove a towel.

30 As a matter of further and specific improvement, there is provided a novel means for holding the towels against slipping when the container or rack is hung from an overhead support, said means comprising a strip 35 of elastic that is so arranged as to bear tightly against the upper end of a towel, and with sufficient force to hold the towel from slipping when the rack is maintained in an upright position.

40 Further and more specific details of construction will hereinafter more fully appear.

In the accompanying drawings forming a part of this specification and in which like 45 characters of reference indicate corresponding parts: Figure 1 is a view in perspective of a towel rack constructed in accordance with the present invention. Fig. 2 is a diagrammatic view in plan showing the manner in which the towel clamping means is 50 assembled with the structure. Fig. 3 is a top plan view, with certain parts omitted, showing the manner in which the sections of the rack are assembled. Fig. 4 is a similar view, showing parts omitted in Fig. 3. Fig. 5 is a fragmentary perspective view of

one of the leaves, showing a modified form of towel clamping device.

The container or rack comprises, in the present instance, four sections or folders, 50 each comprising two members 1 and 2, which may be constructed of any suitable material, such as wood, indurated fiber or the like, and each pair of which is connected, independent of the other, by means of hinges 3, 60 three of these hinges being employed in the present instance, although a greater number may be utilized if found necessary or desirable.

The sections are connected at their top 70 and bottom by metallic or elastic rings 4 and 5, which pass through the successive series of folders, and serve to hold them properly assembled, but at the same time permit them to be readily opened when it is desired 75 to remove or install a towel. The structure as a whole is adapted either to rest upon the ground with the sections open in order to expose the towels to the atmosphere, or to be suspended from an over-head support, 80 to accomplish which a hanger 6 is provided which may be made from a length of wire connected with the upper ring 4.

As a means for holding the towels assembled with the different sections of folders, a clamping means is employed which, as shown in Fig. 1, consists of a length of flat braided rubber 7 which is woven through the upper ends of the successive folder members, one single length of the braided 90 rubber being employed for the purpose. To accomplish this result, as is shown in Fig. 2, one end of the rubber is first passed through an opening in one of the folder members, adjacent to its inner edge, the 95 other end being passed through a similar opening adjacent its outer end, then turned around the opposite side of the folder and passed through the first opening, then passed through an opening adjacent to the 100 inner edge of the second folder, and so on throughout the series. By this arrangement, not only will the elastic clamp be made to operate as a means for retaining the towels in position, but it will also in a 105 measure serve to hold the different folder sections assembled.

Instead of employing a continuous binder or clamp as above described, a single clamp 8 may be employed in connection with each 110 of the folder members as shown in Fig. 5.

In use it is designed that the unfolded

towels shall be suspended by the resilient clamp against the folder members, and the rack either suspended, or left to rest upon the ground in order to admit the towels 5 thoroughly to be aired or dried, and after they have been folded and are again positioned between the members of the rack, the members of each folder are held firmly assembled by a plurality of latches 9 which 10 are pivotally connected with one of the folder members adjacent the one edge and straddle the adjacent edge of the other folder member. By this arrangement the towels will be held in folded position, and 15 at the same time shielded from the entrance of dust and dirt. By reason of the employment of the rings 4 and 5 for holding the series of sections assembled, the latter may be folded flat, so as to occupy but a small 20 space when not in use.

I claim:

1. A towel rack comprising a plurality of connected two-leaved sections adapted to be folded into vertical parallelism, a towel suspending means connecting the sections, and means for holding the leaves of any section closely assembled independent of the other sections. 25
2. A towel rack comprising a plurality of connected two-leaved sections, an elastic towel suspending means connecting the sections, and means for holding the leaves of any section closely assembled independent of the other sections. 30
3. A towel rack comprising a plurality of two-leaved sections, rings connecting the series of sections and disposed adjacent to the 35

upper and lower ends thereof, an elastic towel suspending member threaded through the series of leaves and connecting the same, 40 and means for holding the leaves of any section closely assembled independently of the other sections.

4. A towel rack comprising a plurality of connected two-leaved sections, a link of elastic material threaded through the series of leaves adjacent to their upper ends to provide towel suspending means, rings connecting the series of sections and disposed adjacent to the upper and lower ends thereof, 45 latches carried by one member of each of the sections and arranged to straddle the other member at its edge, and means for suspending the rack from an over-head support. 50

5. A towel rack comprising a plurality of connected two-leaved sections provided adjacent to their upper ends with towel suspending means, the leaves of each section hinged together at their inner vertical edges, and means for holding the leaves of any section closely assembled independent 55 of the other sections.

6. A towel rack embodying two-leaved sections and towel suspending means laced through the two leaves adjacent to their upper ends and connecting the same. 60

In testimony whereof I hereunto affix my signature in the presence of two witnesses.
